UNITED STATES PATENT OFFICE.

LOUIS STEINBERGER, OF BROOKLYN, NEW YORK.

CASE AND CAP FOR TELEPHONE-RECEIVERS.

1,093,951.

Specification of Letters Patent. Patented Apr. 21, 1914.

Application filed January 13, 1913. Serial No. 741,861.

To all whom it may concern:

Be it known that I, LOUIS STEINBERGER, residing at Brooklyn, in the county of Kings and State of New York, have invented certain new and useful Improvements in Cases and Caps for Telephone-receivers, of which the following is a specification.

This invention relates to a telephone receiver casing, and the particular object of 10 the invention is to provide a casing of the usual form, comprising a body part for containing the receiver mechanism, a diaphragm, and a cover for fitting over one end of the casing to retain the diaphragm in position 15 and to form an ear piece, and to provide reinforcing sections upon the body and upon the cover, whereby the connections between said parts may be made more substantial, and less liable to injury.

20 A further object is to provide a metallic ring having threads on its outer periphery and being adapted to be molded rigidly as a relatively integral part of the body of the structure, and to provide a similar metallic ring having the threads on its inner periphery and being adapted to be molded as a relatively integral portion of the cover, the threads of the two metallic rings referred to being of mating proportions, so 30 that the cover may be readily attached to the body in the customary manner, and to form a clamp for retaining the diaphragm.

Other objects and aims of the invention, more or less specific than those referred to 35 above, will be in part obvious and in part pointed out in the course of the following description of the elements, combinations, arrangements of parts and applications of principles, constituting the invention; and 40 the scope of protection contemplated will be indicated in the appended claims.

In the accompanying drawings which are to be taken as a part of this specification, and in which I have shown a merely preferred form of embodiment of the invention: Figure 1 is a transverse, central, sectional view through the cover of a receiver casing, constructed in accordance with this invention; Fig. 2 is a similar view of the 50 body portion of the receiver casing, a diaphragm being illustrated in relative position to be clamped upon the upper surface of the body; and Fig. 3 is a detail perspective view of a portion of one of the reinforcing 55 rings employed, the particular ring here

illustrated being that on the body portion of the casing.

Referring to the drawings for a more detailed description of the structure, the numeral 1 indicates the body portion of the 60 casing generally. The body is formed or shaped in the usual manner with an aperture, as 2, at one end, for the passage of wires, and has its other end flared outwardly, as at 3, to provide an enlarged end portion 65 for receiving the diaphragm illustrated at 4. Encircling the flared end portion of the body is a metallic ring 5. This ring has an annular groove, as 6, formed on its inner surface adapted to receive a portion of the 70 material of the body and providing inwardly projecting annular flanges adapted to project into relatively embedded relation with the material of the body, the lowermost of said flanges extending beneath the shoul- 75 der formed by the material of the body which projects into the groove 6. One or more transversely extending grooves, as 7, in Fig. 3, may be provided, also for receiving a portion of the material of the body. 80 The annular groove 6 effectually prevents telescoping movement of the ring from the body, while the groove or grooves 7 serve to prevent a rotary movement of the ring about the body. The outer annular surface of the 85 ring is provided with threads 7' to be engaged by similar threads 8 formed on the ring 9 carried by the cover.

The cover comprises a disk portion, as 10, having a conical depression 11, and a central 90 opening 12 of the usual or preferred formation, and having an annular pendent flange 13. The ring 9 is fitted within the annular flange 13 and is provided with longitudinal and transverse grooves on its outer surface for receiving portions of the material of the flange 13 in the same manner as the grooves 6 and 7 of the ring 5, above described. The threads 8 are formed upon the inner surface of the ring 9. In order 100 to properly support the disk 4, the ring 6 on the body preferably projects a slight distance beyond the end surface of the body 1, as at 14, and the disk is of a size to rest upon the projecting portion 14 of the ring 6. A 105 pendent ridge 15 is formed upon the under-surface of the disk portion 10 of the cover, and is adapted to engage the upper surface of the disk for retaining the disk in clamped relation with the upper surface of the ring 110.

5, the threaded engagement of the cover with the body serving as a clamp in the usual manner. The ridge 15 is of slightly less diameter than the ring 5 so as to engage 5 the disk in a plane slightly within the ring 5 for improving the vibrating qualities of the disk.

It will be understood that though I have 10 illustrated longitudinal and transverse 10 grooves upon the rings 5 and 9 for retaining the rings in relatively fixed relation to their supporting material, any desired means may be employed for bringing about this result 15 within the scope of this invention, the 15 grooves illustrated being simply illustrative of one manner of rigidly connecting the rings to the body and cover in a simple and inexpensive manner, and leaving the upper surface of the ring smooth.

20 In manufacturing the structure illustrated, it is apparent that the rings may be placed within a suitable mold in proper position, and the fistic material of the structure poured into the mold so that portions 25 thereof will flow into the grooves and harden, so that the rings will become, in effect, an integral portion of the structure and at the same time will serve to materially reinforce the same against fracture, and their 30 presence will enable a corresponding reduction in the proportion of the parts, and a consequent saving of material. The body and cover may comprise any suitable material, but I preferably employ the material 35 known as "electrose."

As many changes could be made in the above construction and many apparently widely different embodiments of this invention could be made without departing from 40 the scope thereof, it is intended that all matter contained in the above description or shown in the accompanying drawing shall be interpreted as illustrative and not in a limiting sense.

45 It is also to be understood that the language used in the following claims is intended to cover all of the generic and specific features of the invention herein described and all statements of the scope of the 50 invention, which as a matter of language, might be said to fall therebetween.

Having thus described my invention what I claim as new and desire to secure by Letters Patent, is:

55 1. In a telephone receiver, a body portion having an annular open end, and a reinforcing ring for said end, said ring having an annular groove for receiving portions of the material of the body for preventing move-

ment of the ring in one direction relatively 60 to the body, and having a transverse groove for receiving portions of the material of the body to prevent movement of the ring in another direction relatively to the body.

2. In a telephone receiver, a body portion 65 having an annular open end, one edge of said ring forming a diaphragm seat, and the opposite edge of said ring having an inwardly 70 projecting annular rib or flange thereon extending into embedded relation in the material of the body.

3. In a telephone receiver casing comprising 75 a body portion having an annular open end, the combination therewith of a reinforcing ring fixed to the material of said body encircling said open end and projecting thereabove to form a diaphragm seat, and the lower edge of said reinforcing ring being formed with an inwardly projecting 80 annular rib or flange extending into embedded relation in the material of the body.

4. A telephone receiver comprising a body portion having an annular open end, a reinforcing ring for said open end being formed 85 with an inwardly projecting annular rib or flange adjacent one edge thereof extending into embedded relation in the body, and said rib or flange being provided with one or more transversely extending grooves into 90 which the material of the body extends, for the purpose set forth.

5. In a telephone receiver structure, the combination with a casing having an annular open end, of a reinforcing ring fixed to 95 the material of said casing for strengthening said open end and said ring projecting above the end of the casing, a cover for the open end of said casing having a separately formed reinforcing ring thereon, and having 100 an annular depression adjacent said reinforcing ring, both of said reinforcing rings having parts whereby they may be connected together for retaining the cover upon the casing, the projecting portion of the ring 105 upon the casing serving as a diaphragm seat for engaging the outer annular edge portion of the receiver diaphragm, and being disposed for forcing the outer annular edge portion of the receiver diaphragm toward 110 the annular depression in the cover.

In testimony whereof, I affix my signature in the presence of two witnesses.

LOUIS STEINBERGER.
